[57] CLAIM

The ornamental design for clothespin, as shown and described.

DESCRIPTION

FIG. 1 is a front elevational view of a clothespin embodying our new design;

FIG. 2 is a top plan view of the design;

FIG. 3 is a bottom plan view of the upper member of the clothespin of FIG. 1;

FIG. 4 is a top plan view of the lower member of the clothespin of FIG. 1;

FIG. 5 is a bottom plan view of the design; and,
FIG. 6 is a cross sectional view taken on line 6—6 of FIG. 2.

The broken line showing of a spring is for illustrative purposes only and forms no part of the claimed design.
